UNITED STATES PATENT OFFICE.

PHILIP BOSCHE, OF NEW PHILADELPHIA, OHIO.

BUGGY-BOOT.

SPECIFICATION forming part of Letters Patent No. 397,578, dated February 12, 1889.

Application filed July 9, 1888. Serial No. 279,429. (No model.)

To all whom it may concern:

Be it known that I, PHILIP BOSCHE, a citizen of the United States, residing at New Philadelphia, in the county of Tuscarawas and State of Ohio, have invented certain new and useful Improvements in Buggy-Boots; and I do hereby declare that the following is a full, clear, and exact description of the same, reference being had to the annexed drawings, making a part of this specification, and to the letters and figures of reference marked thereon, in which—

Figure 1 is a view of a portion of a buggy-box, showing the boot open. Fig. 2 is a sectional view of a buggy-box, showing a part of the boot-frame and one of the retaining-springs properly attached. Fig. 3 is a view showing a small portion of the boot-frame with one of the bars attached thereto, and also a slight modification of the retaining-spring. Fig. 4 is a view showing construction of the bend in the boot-frame. Fig. 5 is a view showing the construction of the corners of the boot-frame.

The present invention has relation to buggy-boots; and its nature consists in the different parts and combination of parts hereinafter described, and particularly pointed out in the claims.

Similar letters of reference indicate corresponding parts in all the figures of the drawings.

In the accompanying drawings, A represents the buggy-box, which may be of the form shown, or it may be of any other desired form, reference being had to attaching the boot-frame. To the boot-frame B are pivotally attached the bars C, said bars being located substantially as illustrated in the drawings. The front or inner ends of the bar C are held in proper position by means of the staples a. The front or inner ends of the bars C are provided with the notches or recesses b, which are for the purpose of engaging the staples a, as illustrated in Figs. 1 and 2. To the front or inner ends of the bars C are attached the springs D, said springs being substantially of the form shown, and, as shown, they consist of straight wire ends. The front

or inner ends of these springs D are so adjusted that they will come below the staples a, and are so adjusted for the purpose of forcing the bars C downward and insuring the recesses b to engage the staples a and hold the boot-frame B in an elevated position, as illustrated in Figs. 1 and 2.

When it is desired to close the frame B, the rear end of said frame is pressed or forced downward, thereby disengaging the recesses b from the staples a, when the frame B is automatically closed by means of the springs D. The outer or rear ends of the springs D are attached to the frame B by means of the eyes c or their equivalents.

For the purpose of providing a strong frame the ends at the rear corners of said frame are provided with the groove d, which receives the metal plate E, said metal plate being first folded, as illustrated in Fig. 5, when the mitered grooved ends are placed together and the metal plate E folded over the corner, as illustrated in said Fig. 5, and secured in that position by means of nails or their equivalents.

For the purpose of forming a strong and durable bend in the frame B the metal plate F is securely attached, substantially as illustrated in Fig. 4. The plate F is for the purpose of strengthening the frame B at the point G where the frame is cut in order to make the bend. It will be understood that the frame B is to be properly hinged to the box A.

In Fig. 3 a slight modification of the spring attachment is shown, which consists in providing the spring-bar H, said bar being riveted to the front or inner end of the bar C, and the spring proper attached to the spring-bar H, substantially as shown in Fig. 3.

Having now fully described my invention, what I claim as new, and desire to secure by Letters Patent, is—

1. The combination of the buggy-box A, having hinged thereto the frame B, the bars C, pivotally attached to the frame B, the recesses b, adapted to engage the staples a, and the springs D, substantially as and for the purpose specified.

2. The combination of the buggy-box A, having hinged thereto the frame B, mitered ends of the frame B, provided with the grooves d, and the metal plates E, adapted to be 5 folded over the ends of said frame B, substantially as and for the purpose specified.

In testimony that I claim the above I have

hereunto set my hand in the presence of two witnesses.

PHILIP BOSCHE.
